UNITED STATES PATENT OFFICE.

JOHN F. FOSTER, OF ARGENTINE, KANSAS.

ROLLER-BEARING.

No. 902,810.

Specification of Letters Patent.

Patented Nov. 3, 1908.

Application filed January 10, 1908. Serial No. 410,167.

To all whom it may concern:

Be it known that I, JOHN F. FOSTER, a citizen of the United States, residing at Argentine, in the county of Wyandotte and 5 State of Kansas, have invented certain new and useful Improvements in Roller-Bearings, of which the following is a specification.

This invention relates to roller-bearings and my object is to produce a bearing which 10 will operate efficiently and reliably and with a minimum of friction.

A further object is to produce a bearing of simple, strong, durable and comparatively inexpensive construction.

15 To this end the invention consists in certain novel and peculiar features of construction and organization as hereinafter described and claimed; and in order that it may be fully understood reference is to be 20 had to the accompanying drawings, in which:—

Figure 1, is a view of the bearing which discloses one-half of the same in side elevation and the other half in central vertical section. Fig. 2, is a central vertical section taken on the line II—II of Fig. 1, the shaft being shown in elevation. Fig. 3, is a transverse section of a part of a bearing of modified form. Fig. 4, is a detail perspective 25 view of the parts of a sectional roller forming part of the invention. Fig. 5, is an edge view of a spacing cage rotatable with the rollers. Fig. 6, is a section on the line 30 VI—VI of Fig. 5.

35 In the said drawings where like reference characters identify corresponding parts, 1 indicates a shaft adapted to be journaled in any suitable manner, and secured upon said shaft by a key 2 or otherwise is a pair of 40 cones or collars 3 which cones or collars may be secured together by tie-bolts as at 4 if desired. The cones 3 are of identical construction, that is to say they are all step shape in cross section and they are arranged 45 with their apex or smaller ends together, so as to conjointly produce a central annular groove 4. Their intermediate steps 5 have rounded riser portions or shoulders 6 and their top steps 7 are identical with their peripheries at their points of greatest diameter.

50 A ring or band comprises two sections 8 and 9 fitted together and interlocked in such relation in any suitable manner (not shown). These ring or band sections are of considerably greater diameter than the cones or collars described and concentrically surround

the latter. Internally the sections 8 and 9 are step shaped so as to conjointly form an internal groove 10 in the vertical plane of groove 4. They are provided with intermediate steps 11 which terminate in rounded riser portions or shoulders 12, and outward of said risers are steps 13.

14 indicates a ring fitting loosely in the groove 4 and having its tread or outer face 65 tapering inwardly at its edges as at 15.

16 indicates a ring fitting loosely in groove 10 and provided internally with a central rib 17.

18 indicates rollers of reduced diameter 70 centrally to form annular grooves with rounded edges. The rollers have their ends rounded and are provided with reduced portions 19. The rollers are arranged with their reduced portions in the vertical plane 75 of rings 14 and 16. Their reduced end portions engage portions 7 and 13 and their larger or intermediate portions engage steps 5 and 11 and risers or shoulders 6 and 12. In practice one or more of these rollers will 80 be of sectional construction, that is to say, one section will be provided with a passage 20 and the other with a stem 21 to extend through said passage, the stem-equipped section having tongues 23 to engage grooves 24 85 in the section provided with the passage, this tongue and groove relation interlocking the sections together so that they will rotate as one.

25 indicates a series of substantially spool shaped rollers having their reduced central portions engaging the outer surface or periphery of ring 14 and their non-reduced or end portions engaging the grooved central portions of rollers 18.

26 indicates similar but larger rollers having their grooved portions engaging the inwardly projecting rib 17 of ring 16, and their end portions engaging the reduced central portions of rollers 18, it being noticed 95 that there is a roller 25 and a roller 26 between adjacent rollers 18 and that the axes of said rollers 25 and 26 are in radial alinement. These rollers are spacing rollers, that is they tend to maintain the main rollers 18 100 at uniform distances apart, it being also noticed that the inner series of rollers, 25, are prevented by the main rollers from moving outward and that the latter prevent the outer series of rollers, 26, from moving inward. The ring 14 prevents the inner series 105 of rollers from moving inward and is pre- 110

vented by said rollers from assuming a position eccentrically of the shaft. The series of rollers 26 are likewise prevented from moving outward by ring 16 and maintain the latter concentrically with respect to ring 14 and the shaft. As a precautionary measure I have provided additional means for spacing rollers 18, the same comprising a pair of rings 27 fitting between cones or collars 3 and the band or ring surrounding the same and adjacent to the ends of rollers 18 and provided with oppositely bowed lugs 28 that fit around the reduced ends 19 of said rollers, it being preferred that ordinarily the 15 lugs shall be out of contact with the ends of said rollers. The rings 27 are connected together by tie-rods 29 which extend loosely through passages 30 formed in the rollers to receive them, the said rods having shoulders 20 31 near their ends to prevent the rings from coming into contact with the reduced ends of the rollers.

In Fig. 3 the rollers 18 (one only appearing) are of tapering form and the same is 25 true of the rings 14 and 16 and of the spacing rollers 25 and 26. A bearing of this type is desirable under certain conditions not necessary to mention.

In practice rotary movement imparted to 30 shaft 1 is transmitted by the cones or collars to rollers 18, and by the latter to the outer ring or band, it being noted that the rollers 18 operate without rubbing friction. It will be also noted that no rubbing friction is 35 engendered between said rollers and the spacing rollers because of the rolling contact between them, it being further noted in this connection that the inner ring 14 is driven in the same direction as the cones or collars by 40 the inner series of spacing rollers, but that the outer ring is driven by the outer series of spacing rollers, in the opposite direction. It will also be apparent that the bearing will 45 operate if the power is applied to the outer band or ring, the result in this case being to transmit rotation through the rollers to the cones or collars and to the shaft. In the event that either of the rings 14 or 16 or 50 any of the spacing rollers should be broken, the cage will maintain the main rollers at the requisite distance apart and thus prevent any possibility of said rollers coming 55 into contact and grinding upon each other.

From the above description it will be apparent that I have produced a roller-bearing 55 which embodies the features of advantage enumerated as desirable, and I wish it to be understood that I reserve the right to make such changes as properly fall within the 60 spirit and scope of the appended claims.

Having thus described the invention what I claim as new and desire to secure by Letters Patent, is:—

1. A roller-bearing, comprising a pair of 65 collars secured together and reduced to form

an annular groove, a band or ring surrounding said collars provided with an internal groove in the vertical plane of the first-named groove, a circular series of rollers between and engaging said collars and said band, a ring within and spaced from the first-named groove, a circular series of spacing rollers peripherally engaging said ring and the adjacent main rollers, a ring interposed between and spaced from the main 70 rollers and said band, and a circular series of spacing rollers engaging the adjacent main rollers and the inner side of the last-named ring.

2. A roller-bearing, comprising a shaft, a 80 pair of collars secured thereon and reduced at their adjacent ends to form an annular groove, a band concentrically surrounding said collars and formed internally with an annular groove or channel, a circular series 85 of main rollers interposed between and engaging said collars and band and diametrically reduced centrally, a ring occupying the groove of said collars, a ring occupying the groove of said band, a circular series of 90 spacing rollers peripherally engaging the first-named ring and the reduced portion of the main rollers, and a second series of spacing rollers engaging the grooved portion of the main rollers and the inner side of the 95 ring occupying the groove of said band.

3. A roller-bearing, comprising a shaft, a pair of collars secured thereon and reduced at their adjacent ends to form an annular groove, a band concentrically surrounding 100 said collars and formed internally with an annular groove or channel, a circular series of main rollers interposed between and engaging said collars and band and diametrically reduced centrally, a ring occupying 105 the groove of said collars, a ring occupying the groove of said band, and provided with an inwardly projecting circular rib, a series of spacing rollers engaging the reduced portions of the adjacent main rollers and the 110 periphery of the inner ring, and a second series of spacing rollers engaging the grooved portions of the adjacent main rollers and reduced centrally to engage the inwardly projecting rib of the ring occupying 115 the groove of said band.

4. A roller-bearing, comprising a pair of collars secured together and reduced to form 120 an annular groove, a band or ring surrounding said collars provided with an internal groove in the vertical plane of the first-named groove, a circular series of rollers between and engaging said collars and said band, a ring within and spaced from the first-named groove, a circular series of spacing rollers peripherally engaging said ring and the adjacent main rollers, a ring interposed between and spaced from the main 125 rollers and said band, a circular series of spacing rollers engaging the adjacent main 130

- rollers and the inner side of the last-named ring, and a skeleton cage comprising a pair of rings between the collars and said band at opposite ends of the main rollers and provided with oppositely bowed lugs projecting inwardly contiguous to and at opposite sides of said main rollers, and tie-rods extending through said main rollers and said lug-equipped rings.
- 10 5. A roller-bearing, comprising a shaft, collars secured thereon, a band concentrically surrounding said collars, a circular series of rollers between and engaging said collars and said band, one or more of said
- 15 rollers comprising interlocked sections, one section having an axial passage and the companion section having a cylindrical
- stem extending through said passage, a ring surrounding and spaced from said collars and arranged inward of the main rollers, a second ring surrounding the main rollers and within said band, a circular series of spacing rollers engaging the inner ring and the main rollers to space the latter apart, and a second series of spacing rollers engaging the outer ring and the main rollers and cooperating with the first-named spacing rollers in spacing the main rollers apart. 25

In testimony whereof I affix my signature, in the presence of two witnesses.

JOHN F. FOSTER.
